CLAIM

The ornamental design for a glove palm design, as shown.

DESCRIPTION

FIG. 1 is a view showing the glove palm;

FIG. 2 is a left side view of the glove shown in FIG. 1;

FIG. 3 is a right side view of the glove shown in FIG. 1;

FIG. 4 is a top view of the glove shown in FIG. 1; and,

FIG. 5 is a bottom view of the glove shown in FIG. 1.

The broken line showing of a glove in FIG. 1 is included for the purpose of illustration and does not form a part of the claimed design.
